DESCRIPTION

FIG. 1 is a front, right, top perspective of the dimpled flashlight with octagonal head thereof.

FIG. 2 is a front view of the dimpled flashlight with octagonal head thereof.

FIG. 3 is a rear view of the dimpled flashlight with octagonal head thereof.

FIG. 4 is a right-side view of the dimpled flashlight with octagonal head thereof.

FIG. 5 is a left-side view of the dimpled flashlight with octagonal head thereof.

FIG. 6 is a top view of the dimpled flashlight with octagonal head thereof; and,

FIG. 7 is a bottom view of the dimpled flashlight with octagonal head thereof.

The broken lines are for illustrative purposes only and form no part of the claimed design.
